UNITED STATES PATENT OFFICE.

LEWIS E. CURTIS, OF KENILWORTH, ILLINOIS, ASSIGNOR TO AMES STEEL LATH COMPANY, OF ST. LOUIS, MISSOURI, A CORPORATION OF MISSOURI.

MACHINE FOR SLITTING SHEET METAL.

1,071,712.

Specification of Letters Patent.

Patented Sept. 2, 1913.

Application filed December 5, 1912. Serial No. 735,068.

To all whom it may concern:

Be it known that I, LEWIS E. CURTIS, a citizen of the United States, residing in Kenilworth, in the county of Cook and State of Illinois, have invented a new and useful Improvement in Machines for Slitting Sheet Metal, of which the following is a specification.

This invention relates to improvements in machines for slitting sheet metal.

Sheet metal slitting machines, such as are used to slit or cut sheet metal to be subsequently expanded to form metal lath, are now commonly made with the slitters or cutters mounted in a hingedly connected two-part housing, one slitter or cutter being journaled in each part, to thereby permit the upper part of the housing to be swung back on the hinge connection and allow access to the slitters or cutters.

In practice, the upper part of the housing, or housing cap, is swung back as often as once or twice per day, and this repeated swinging back of the housing cap and the repeated heavy shocks on the machine tending to separate the two parts of the housing, which result from the impact of the metal sheets against the slitters each time a sheet strikes against the same, soon wear the hinge connections and thus destroy the adjustment between the overlapping slitters or cutters and hence decreases the efficiency of the slitting operation. As is well known, the slitters or cutters are very finely adjusted and this fine adjustment must be maintained to insure the successful operation of the machine during the heavy wear to which the slitters are necessarily subjected.

The object of my invention is to provide a slitting machine of the type above referred to, having adjustable means to compensate for all the wear on the members forming the hinge connection between the two parts of the housing.

The invention furthermore consists in the improvements in the parts and devices and in the novel combinations of the parts and devices herein shown, described or claimed.

In the drawing forming a part of this specification, Figure 1 is a longitudinal, vertical sectional view of a slitting machine of well known form and having my improvements embodied therein and Fig. 2 is an end elevation of the structure shown in

Fig. 1, and being upon a somewhat smaller scale.

In the drawing 10 denotes the bed or base which is of suitable form and adapted to support various parts of the slitting machine. The slitting machine, as shown, comprises a lower housing formed of two members 11, 11, slidably and adjustably mounted in ways on the bed or base 10. Mounted in suitable bearings in the housing 11, 11, is the arbor 12 on which are mounted the lower slitters or cutters 13. Pivotaly connected to the housing 11, 11, by connections more particularly hereinafter described, is the housing cap 14 in which is mounted in suitable bearings, the arbor 15 supporting the upper set of slitters or cutters 16, the slitters 16 intermeshing with or overlapping the slitters 13 in the usual manner.

The hinge connections between the housing and the housing cap comprise two lower hinge pieces 17, 17 secured to the two members 11, 11 of the housing by means of tongues 18, fitting in coöperating grooves 19, and a plurality of screws 20. Each hinge piece 17, as shown, is provided with a pair of spaced members 21 adapted to receive the hinge pins 22 and between the members 21 and mounted on the pins 22 are the upper hinge pieces 23, each of said hinge pieces 23 being provided with a threaded portion 26 which passes through bored lugs 27 formed integral with the housing cap 14. Mounted on each threaded portion 26 is an adjusting nut 28, by means of which the housing cap 14 may be adjusted relatively to the upper hinge pieces 23 to thereby compensate for any wear between the hinge forming elements. Each upper hinge piece 23, as shown, is provided with vertically elongated slots 29 through which pass set screws 30, the latter being threaded in the housing cap 14. Between the heads of the screws 30 and the upper hinge pieces 23 are provided washers 31, and as will be obvious, the set screws 30 are adapted to clamp or hold in position, the upper hinge pieces relatively to the housing cap 14 after any adjustment has been made by the nuts 28.

The housing cap 14 is held in proper position, during the slitting operation, by any suitable means such as the screws 32 which pass through the housing cap 14 into threaded sockets in the members 11, 11, forming the housing,

and the hinge pins 22 are held in proper position by any suitable means such as cotter pins 33.

From the foregoing description, it will be seen that I have provided means for compensating for wear on the hinge forming elements, said means being so arranged that the hinges on each side of the machine are independently adjustable.

10 Although I have herein shown and described what I now consider the preferred embodiment of my invention, yet it will be understood by those skilled in the art, that various changes and modifications may be 15 made in the details of construction and arrangement of parts without departing from the spirit of the invention, and all such changes and modifications are contemplated as come within the scope of the claims appended hereto.

I claim:

1. A slitting machine of the character described comprising, in combination: a housing; a housing cap; coöperating slitters mounted in the housing and housing cap; a hinge connection between the housing and housing cap; and means for compensating for wear on the hinge connection caused by the repeated shocks on the machine which occur when the metal sheets strike the slitters, substantially as specified.

2. A slitting machine of the character described comprising, in combination: a housing; a housing cap; coöperating slitters mounted in the housing and housing cap; a hinge connection between the housing and housing cap; and means for compensating for wear on the hinge connection including an adjustable connection between one of the 40 elements of the hinge connection and the housing cap, substantially as specified.

3. A slitting machine of the character described comprising, in combination: a housing; a housing cap; coöperating slitters mounted in the housing and housing cap; a hinge piece mounted on the housing; a second hinge piece mounted on the housing

cap and coöperating with said first named piece; and means for adjusting one of said hinge pieces relatively to the member to 50 which it is secured, substantially as specified.

4. A slitting machine of the character described comprising, in combination: a housing; a housing cap; coöperating slitters 55 mounted in the housing and housing cap; a hinge piece on the housing; and a second hinge piece coöperating with the first named hinge piece and adjustably mounted on the housing cap, to thereby provide for adjustment between the housing and housing cap to compensate for wear on the hinge connection, substantially as specified.

5. A slitting machine of the character described comprising, in combination: a housing; a housing cap; coöperating slitters 65 mounted in the housing and housing cap; two sets of hinge connections between the housing and the housing cap; and independent means for compensating for wear on 70 each of the hinge connections, substantially as specified.

6. A slitting machine of the character described comprising in combination: a housing; a housing cap; coöperating slitting devices mounted in the housing and housing cap; means for connecting the housing and housing cap together and adapted to permit relative movement therebetween; and means for compensating for wear on said connecting means, substantially as specified.

7. A slitting machine of the character described comprising, in combination: a housing; a housing cap; coöperating slitting devices mounted in the housing and housing cap; a hinge piece detachably secured to the housing; and a second hinge piece, coöperating with the first named hinge piece, adjustably mounted on the housing cap, substantially as specified.

LEWIS E. CURTIS.
